UNITED STATES PATENT OFFICE.

JACOB K. GRIFFITH, OF LATROBE, AND JOHN SLATTERY, OF PHILADELPHIA, PENNSYLVANIA.

METAL-MOLD.

SPECIFICATION forming part of Letters Patent No. 587,728, dated August 10, 1897.

Application filed June 26, 1895. Serial No. 554,089. (No model.)

To all whom it may concern:

Be it known that we, JACOB K. GRIFFITH, of Latrobe, in the county of Westmoreland, and JOHN SLATTERY, of Philadelphia, in the 5 county of Philadelphia, State of Pennsylvania, have invented a new and useful Improvement in Metal-Molds, of which the following is a full, clear, and exact description, reference being had to the accompanying drawings, forming part of this specification, in which—

Figure 1 is a top plan view of a mold constructed in accordance with our invention; and Fig. 2 is a side elevation of the same, 15 partly broken away. Fig. 3 is a side elevation, partly broken away, showing another form of our invention; and Fig. 4 is a top plan view of the same with a portion broken away. Fig. 5 is a side elevation, partly broken 20 away, of a third form of our invention. Fig. 6 is a vertical section on the line VI VI of Fig. 5. Figs. 7 and 8 are end views of one of the molds employed, showing the block of refractory material over which the metal flows 25 into the mold. Fig. 9 is a longitudinal section of a fourth form of our invention, and Fig. 10 is a cross-section on the line X X of Fig. 9.

Our invention relates to the casting of a 30 series of ingots or other articles in metal-molds, and is designed to provide an improved arrangement of the flask and the metal-molds contained therein, whereby each article or ingot is fed uniformly and continuously during 35 the cooling of the metal therein, and the molds are easily nested together for casting and separated after casting.

In Figs. 1 and 2 of the drawings, wherein we illustrate a simple form of our invention, 40 a flask is employed in the form of a Maltese cross, this flask being preferably built up in sections, as shown, the lower section 2 having integral therewith the base-plate 3, while upon the upper section 4 rests the top closing- 45 plate 5. Each arm of the flask is filled with a vertical series of molds which may be superimposed upon each other, and are formed by removable mold-sections 6. The lowermost 50 of these sections is provided with a flat bottom resting upon the base-plate, while in its

upper portion is provided the open matrix portion, which is of the form of the article to be produced, in this case a brake-shoe. The upper face of the matrix-cavity is formed by the lower convex face of the next mold-section above, this mold-section having in its upper face a matrix-cavity, which is closed by the lower convex face of a similar section above it, these similar sections being superimposed upon each other until the flask is 60 filled, the matrix-cavities of the uppermost series being closed by the top plate of the mold, which is suitably formed on its under face to give the required shape to the cavity. The center of the flask is occupied by a vertical 65 runner or gate, which is formed of separable interfitting sections 7, having registering vertical holes forming the main gate, from which lead the branch gates 8, communicating with the sprue 9 of each mold, this sprue being 70 formed by a hollow block of refractory material set in a receiving-cavity in the inner end of each mold-section.

The operation is apparent, the molds and central runner being built up within the flask, 75 whose sections are placed one upon the other until the desired height is obtained, when, the top closing-plate being applied, the metal is poured into the central gate and thence passes into each matrix-cavity in the several arms. 80

In Figs. 3 and 4 we show another form of our invention arranged for the casting of ingots. In this form the side arms of the flask are extended laterally and several horizontal series of molds are nested therein. The upper faces of the arms of the base-plate are inclined upwardly to the central portion of the flask, so that the molds 6' lie in inclined positions, each resting on top of the one beneath it and each containing an entire matrix-cavity 90 for the ingot, this cavity preferably tapering from the gate end toward the outer end, so as to allow easy drawing of the mold. The main central runner is formed with separable sections 7', these sections extending along the 95 inner face of the arms and formed with side apertures or gates 8', which lead into each vertical series of molds. The upper flask-section is provided with an upwardly-inclined rim to inclose the upper molds of each series. In 100

this form we show a bottom runner 10, communicating with the central gate and arranged for bottom pouring, a sink-head 11 being provided at the upper end of the central 5 gate in order to feed molten metal to the upper molds during their cooling.

In Figs. 5 and 6 we show the inclined ingot-molds 6" arranged in a different manner, the horizontal series being stacked one above the 10 other on each side of a central gate, this gate being built up of separable sections 7", which form longitudinal gates 12, parallel with each other and communicating alternately at the ends and at the center by vertical openings 15 or gates 13. Each horizontal gate is provided with the sprues or gates 8", leading into the inclined molds, and to the center of the lowermost gate leads the bottom runner 10', through which the molten metal is fed. A 20 sink-head 11' is provided, and to prevent sticking of the ingot to the under side of the mouth portion of the mold, over which portion the metal flows and would tend to melt and weld it to the ingot, we recess this under portion, as 25 in Fig. 7, and fill it in with a block of refractory material 14. The molds may, if desired, be arranged so as to rest on one edge instead of flat upon one side, in which case we place the refractory material 14 in the corner, as 30 shown in Fig. 8.

In the form of Figs. 9 and 10 the flask is provided with a base 3', having its face arranged in two series of steps 15, each step having a central flat portion and thence inclined downwardly in each direction, as shown in Fig. 10. The molds 6" rest upon the steps and are held in place by cover-plates 16, the runner-bricks 7" resting upon the central flat portions of the steps and communicating with 35 each other, as shown. Sink-heads 11" are provided, one for each series of molds, and to the central lowermost portion of the gate leads the bottom runner 10'.

We prefer to use the bottom-pour arrangement wherever the vertical series of metal-molds is employed, although the top pour of Figs. 1 and 2 may be used, if desired.

In casting with the bottom runner metal rising in the central gate passes into the lower 50 molds and fills these first, it then rising and filling the upper ones successively. The advantage of this is that a stream of hot molten metal flows past the entrance of each filled mold while its ingot is cooling, thus feeding 55 each ingot as it shrinks, preventing piping therein.

By placing the molds in an inclined position, as shown, the metal flows continuously down the side and there is no danger of shells 60 or scabs forming on the sides of the ingot, as is frequently the case from top pouring when the molds are arranged vertically. Moreover, there can be no splashing of the metal on the side of the ingot and the mold is thoroughly 65 vented, the air being forced out of the top portion of the mold which is last filled. The inclination also causes one series of molds to fill

completely before the next higher series commences to fill.

By the words "upwardly-extending main 70 gate or runner" of claim 9 we intend to cover not only the main gate of Fig. 3, all portions of which extend vertically, but also gates whose general direction is upward—such as, for instance, in Figs. 5 and 9, wherein portions of this gate are substantially horizontal, while the general direction of flow is upward.

The advantages of our invention will be obvious to those skilled in the art, since a large number of metal-molds may be nested together within a single flask and all filled at the same operation. No skilled labor is necessary in assembling the parts, and piping is effectually prevented.

Many changes may be made in the form 85 and arrangement of the parts without departure from our invention, since

What we claim is—

1. The combination with a flask, of a series 90 of separate metal-molds fitting therein, said molds being superposed one above the other, and a separate vertical runner of refractory material, having branch gates leading into the matrix-cavities of the metal-molds; substantially as described.

2. The combination with a flask having 95 arms radiating from a common center, of separate metal-molds superposed upon each other in each arm of the flask, and a central vertical runner of refractory material, having branch 100 gates leading to the mold-cavities; substantially as described.

3. The combination with a flask composed 105 of several horizontally-divided sections, of a series of separate metal-molds fitting therein, said molds being superposed one above the other, and a separate vertical runner of refractory material having branch gates leading into the matrix-cavities of the metal-molds; substantially as described.

4. The combination with a flask, of a series 115 of separate metal-molds fitting therein, said molds being superposed one above the other, a separate vertical runner of refractory material, having branch gates leading into the matrix-cavities of the metal-molds, and a bottom runner leading to the vertical runner; substantially as described.

5. The combination with a flask, of a series 120 of separate metal-molds arranged in an inclined position therein, and a gate of refractory material having branches leading into the upper ends of the mold-cavities; substantially as described.

6. The combination with a flask, of a series 125 of separate metal-molds arranged in an inclined position therein, and a bottom-pour runner arranged to feed the metal into the upper ends of the mold-cavities; substantially as described.

7. The combination with a flask, of a series 130 of molds arranged in an inclined position therein, and a central gate having branches leading to the molds, each mold having the

under side of its upper end provided with a layer of refractory material, substantially as described.

8. The combination with a separate bottom support having an inclined upper face, of a series of separate metal-molds placed thereon in an upwardly-inclined position and superimposed upon each other, and a bottom-pour gate of refractory material passing through

10 said support and having branches leading to the upper end of each mold-cavity.

9. In casting apparatus, the combination with an upwardly-extending main gate or runner, of upwardly-inclined molds having

15 their upper ends connected to the main runner by branch gates, said molds being arranged at successively higher levels, and a

bottom runner leading to the lower portion of the main runner, whereby the metal flows downwardly over the side or sides of the 20 lowest mold and then upwardly through the main gate, past the branch gate of such mold to a mold at a higher level, at the same time feeding the shrinkage in the first-filled mold.

In testimony whereof we have hereunto set 25 our hands.
